BEAM THERAPY UNIT

Donald Thomas Green, Ottawa, Ontario, Canada,
assignor to Eldorado Mining and Refining
(1944) Limited, Ottawa, Ontario, Canada, a
corporation of Canada

Application March 8, 1951, Serial No. 214,488

9 Claims. (Cl. 250—106)

1

This invention relates to a beam therapy unit and more particularly to an apparatus for controlling the beam in such a unit.

In designing a safe and practical therapeutic machine to utilize a beam of high energy gamma radiation from a radio-active material such as Co⁶⁰ it is necessary to provide means for closing off the beam of radiation from a remote point. Because of the serious consequences of an excess of radiation, it is highly important that the possibility of the means for controlling the radiation beam failing to function be minimized. There are two alternative methods of dealing with the problem: one is to remove the radio-active material to a position from which the emission of radiation is a safe quantity, and the other method is to maintain the radio-active material in the same position and to interpose heavy shielding.

If a method is adopted in which the source of radio activity is moved, this may consist of moving the radio-active source behind a shield or moving it away from the patient so as to provide increased distance. In one recently developed method employing this principle, the radio active material is removed through a bed of mercury, thus making use of the high density of the mercury to multiply the effect of increasing the distance. Methods such as these are not in compliance with desirable safety standards, in view of the danger of mechanical failure.

Previously developed devices based upon the principle of interposing a shielding material, the radio active substance remaining stationary, have employed mechanical methods such as swinging a shield into the path of the beam. Even if the difficulties of moving heavy shielding material quickly and positively are overcome, there remains too great a possibility of failure for such methods to be completely satisfactory.

The present invention is a development of the second method in that the radio-active material remains stationary, but the possibility of the means for closing off the beam failing to function is minimized by using as a shielding material, a high density liquid such as mercury. A reservoir for the dense liquid material is provided at a higher level than a sealed outlet port for the beam and is connected thereto by a passage. The beam is released by driving the dense liquid material from the outlet port into the upper reservoir by means of liquid or compressed gas such as air of high transmissibility to radiation. The beam is closed off by allowing the high density liquid to flow into the outlet port under the influence of gravity. Positive operation is thus provided where it is

2

most important for reasons of safety, namely to close off the beam. To develop the full advantages of the present invention and to design a practical therapeutic machine having a full range of operation, it is necessary to provide for rotation of the beam preferably through at least a right angle. The fulfilment of this requirement in a machine based upon the present principle, calls for further inventive features as particularly described and claimed herein.

In figures which illustrate the preferred embodiment of this invention:

Figure 1 is a plan view.

Figure 2 is a section view on the line A—A in Figure 1.

Figure 3 is a schematic diagram of a system based on the preferred embodiment.

In the drawings which illustrate the preferred embodiment of this invention, numeral 10 designates a source of continuous radiation such as Co⁶⁰; continuous being used to distinguish between a source of radiation comprising a radio-active material which emits high energy gamma radiation and radiation by electrical energy such as X-ray equipment. The source of radiation 10 is enclosed within a container 11 composed of a sufficient thickness of high density material having low transmissibility such as lead to absorb radiation from source 10 which is in excess of a safe quantity. Means of access to source of radioactivity 10, is provided such as a plug 12 engaging a vertical passage 13, or alternatively lateral access may be provided for.

The source of radiation 10 is located approximately at the centre of container 11 which may conveniently be in the form of a vertical cylinder of approximately equal diameter and height. The edges of the cylinder may be broken off as shown in Figure 2 to save material and to achieve a container in which the thickness of high density shielding material is approximately the same in every direction.

An outlet port 14 extends from the surface of container 11 to the source of radiation 10 to provide for the emission of a beam. This outlet port is preferably conical in shape in order to conserve the amount of mercury or other fluid metal required, as it is important to keep the volume of mercury to a minimum, not only for reasons of economy, but in order that an unnecessarily large amount of the dense fluid material will not have to be moved in operating the device. The slope of the sides of conical outlet 14 must be sufficient to allow for the maximum size of beam required and the choice of a suitable angle of

slope is also conditioned by the angle through which the container is to be tilted. Outlet 14 is located as shown in Figure 2 with its apex adjacent to source of radiation 10 and extends to the base of container 11. A window 15 which may be of stainless steel or of other material having a low absorption is horizontally disposed near the apex of outlet 14 to provide a seal between the interior of outlet 14 and source of radiation 10. In the lower part of outlet 14 is another window 16 which may also be of stainless steel and which should be slightly sloped to facilitate draining of the mercury and to increase the angle through which the container can be revolved. The distance between window 16 and source 10 should be sufficient, having regard to the comparative densities of the mercury in outlet 14 and the material of which container 11 is composed, to afford protection against radiation approximately equal to the protection given in other directions. As a safety measure, an additional window 17 flush with the exterior of container 11, may be located below window 16.

The angle through which the unit illustrated in Figure 2 can be revolved about an axis perpendicular to the paper upon which this figure is drawn will be dependent upon two limiting positions. The unit in Figure 2 cannot be rotated counterclockwise past the position at which window 16 is horizontal without trapping mercury which will not be driven out of outlet port 14 by the compressed air. Similarly the unit cannot be rotated in a clockwise direction past the position at which side 18 of outlet port 14 is horizontal. The angle through which the unit can be revolved without interference with its operation henceforth designated as "the angle of tilt" will not therefore be greater than one hundred and eighty degrees (180°) minus the dihedral angle between the surface of window 16 and a plane tangential to side 18 of cone shaped outlet 14 at the lowest point of intersection of side 18 and window 16. Another way of expressing this is:

$$\theta = 180 - (\alpha - \beta)$$

where

θ is the angle of tilt

α is the base angle of the cone

β is the maximum angle of slope of window 16.

Where window 16 is irregular in shape the effective angle of slope for draining purposes will be its maximum angle; which indicates that a slight increase in the angle of tilt may be obtained by providing an annular drain around the circumference of window 16 the trough of which is at a greater slope than the remainder of the window or alternatively draining pipes could be provided in window 16. The object of many of the limitations to the angles of slope from the horizontal of the integers to be described is to preserve the angle of tilt from being limited by factors other than the slopes of side 18 and window 16.

Two pipes, 19 and 20 connect outlet 14 to a reservoir 21. The angle of slope of pipes 19 and 20 should be less than that of side 18 and greater than that of sloping window 16, in order that the mercury may be driven upward into reservoir 21 through pipes 19 and 20 at all effective angles of tilt. In order that the angle of slope of pipes 19 and 20 be less than that of side 18, it is necessary that the pipes branch out on either side of outlet 14 as illustrated in Figure 1. A

horizontal pipe 22 joins pipes 19 and 20 to the bottom of outlet 14. A sump 23 provides access between pipe 22 and the interior of outlet 14 and should be so shaped that there will always be a mercury seal to prevent air from escaping from the interior of outlet 14 through pipe 19 or 20 into reservoir 21. Reservoir 21 should be shaped so that its base 24 is at an equal or greater slope than window 16 and its interior side wall 25 is at an equal or lesser slope than side 18 in order that there will always be a downward inclination to the base and interior side walls of the reservoir throughout the effective angle of tilt of the unit. If the exterior of container 11 is cylindrical in shape as illustrated in Figures 1 and 2, reservoir 21 will be crescent shaped and either horn of the crescent should be connected to pipes 19 and 20 as at 26 and 27. The volume of reservoir 21 should be such that when the mercury has been fully driven out of outlet 14 into sump 23, a space is left in reservoir 21 containing compressed air which exerts a pressure not greater than the pressure used to drive the mercury up into reservoir 21.

On the same side of outlet 14 as reservoir 21, is an inlet pipe 28 for the admission of compressed gas, preferably air. A low density fluid may alternatively be used if necessary modifications to the system are made. Pipe 28 branches into a pipe 29 which runs to the apex of outlet 14 and pipe 30 which runs to the base of outlet 14 at a point which is diametrically opposite to the centre of sump 23. In order to prevent mercury from flowing out through pipe 29 or 30 at various angles of tilt, the slope of pipe 29 should be greater than that of window 16 and the slope of pipe 30 should be equal to or less than the slope of side 21. Branch pipes 29 and 30 are provided so that whatever the angle of tilt, compressed air can be supplied to the upper level of the mercury in outlet 14 rather than being bubbled through the mercury.

Sufficient mercury or other high density fluid having a high absorbtivity to radiation is provided completely to fill outlet 14 and partially to fill pipes 19, 20, 29 and 30. When compressed air is supplied through pipe 28, the mercury is forced through pipes 19 and 20 up into reservoir 21 and outlet 14 is filled with compressed air. The result is to release the beam since the high density material which filled outlet 14 has now been replaced by low density material. When pipe 28 is opened to the atmosphere, the air in outlet 14 will be released to the atmosphere and the mercury in reservoir 21 will flow into outlet 14 filling it under the influence of gravity and the pressure of the air which has been compressed in reservoir 21.

When the mercury is in outlet port 14 the air in reservoir 21 is preferably at atmospheric pressure so that it will be compressed as mercury is forced into the reservoir to form an air cushion against the mercury flowing into the reservoir when the beam is released and to assist in overcoming the initial inertia of the mercury when the mercury is returned to outlet port 14 to close off the beam. The resistance to flow caused by the capillary action of passages 28, 29 and 30 provides a cushioning action against the surge of the mercury when the beam is closed off.

The operating controls are schematically illustrated in Figure 3 in which an air compressor 31 supplies air through an air hose 32 to pipe 28. A pressure switch 33 with a low differential, which is connected by a communicating passage

34 to reservoir 21 switches off the air compressor 31 when all of the mercury has been forced out of the interior of outlet port 14 and it also provides a convenient means of adjustment of the volume of mercury forced out of outlet 14 since the pressure produced in reservoir 21 is a direct function of the reduction of the volume of air in reservoir 21 which in turn is equal to the volume of mercury forced out of outlet port 14. A solenoid valve 35 is provided to release air from outlet port 14 through pipe 28 into the atmosphere. A source of electrical energy 36 operates air compressor 31 and closes solenoid valve 35 until the circuit is broken by opening switch 37 or by pressure switch 33. Switch 37 is located so that it will turn off the air compressor and open solenoid valve 35, whereas switch 33 is positioned so that it will switch off air compressor 31 but will not open solenoid valve 35.

The beam is turned on by closing switch 37 which may be remotely located. This starts the air compressor 31 and at the same time closes the normally open solenoid operated valve 35. The air compressor 31 then builds up air pressure in outlet port 14 until the volume of mercury displaced compresses the air in reservoir 21 to the point at which the pressure switch 33 (normally closed) opens and thus stops the compressor 31. If there is leakage anywhere in the system above the mercury level in outlet 14, when the level of mercury in outlet 14 has as a consequence risen to a point which causes a change in the pressure in reservoir 21 equal to the differential of switch 33, the compressor starts again and re-establishes the mercury level in outlet port 14. As long as switch 37 is closed the mercury level in outlet port 14 is maintained between these two limits, and by choosing the differential of the switch 33, the ratio of the volume of reservoir 21 to the volume of outlet port 14, the air pressure in outlet 14 above the mercury, and the shape and dimensions of sump 23, the differential of the mercury level in outlet port 14 in the "on" condition can be made very small and maintained between two known points below the level of window 16. To turn the unit "off" the switch 37 is opened which will open the solenoid valve 35 and release the air pressure in outlet port 14 until it becomes equal to that of the atmosphere. The mercury in reservoir 21 will then flow into outlet 14, due to the force exerted by gravity and assisted by the air pressure in reservoir 21. If the source of electrical current or any part of the chain of equipment preceding the mercury level in outlet 14 fails the unit will turn "off." It cannot become stuck in the "on" position short of failure to open of solenoid valve 35. A simple manually operated valve may be added in parallel with valve 35 which could be operated with a long rod at a safe distance to safeguard against this eventuality.

It will be appreciated from the foregoing that a simple practical unit which operates positively to close off the beam has been designated based on the principle of replacing material of high absorbtivity such as mercury by material of low absorbtivity such as compressed air.

I claim:

1. In a beam therapy unit including radioactive material providing a source of high energy gamma radiation within a container capable of absorbing radiation in excess of a safe quantity, apparatus for releasing and controlling a beam comprising a conical shaped outlet port, a res-

ervoir at a higher level than said outlet port, connecting passages between the base of the outlet port and the base of the reservoir, sufficient mercury within said outlet port to absorb radiation in excess of a safe amount, a window sealing said outlet port to prevent mercury from escaping through the open end of said outlet port while being capable of allowing the transmission of quantities of radiation of therapeutic value, and means for forcing compressed gas into said outlet port to drive the mercury from the outlet port into the reservoir releasing a beam of radiation, means comprising said compressed gas for maintaining said liquid material exteriorly of said outlet port and means for releasing the compressed gas to allow the mercury to return to said outlet port to close off said beam.

2. In a beam therapy unit rotatable about a horizontal axis and including radioactive material providing a source of high energy gamma radiation within a container which absorbs radiation in excess of a safe quantity, apparatus for releasing and controlling the beam comprising a conical shaped outlet port, a sloped window sealing said outlet port to prevent mercury from escaping through the open end thereof while being capable of allowing the transmission of quantities of radiation of therapeutic value, a reservoir at a higher level than and laterally displaced from said outlet port having a base at an equal or greater slope than that of said window and having an inside wall of an equal or lesser slope than the base angle of said conical shaped outlet port, a sump at the lower end of said window, passages linking the base of the sump with the base of the reservoir, sufficient mercury within said outlet port to prevent the transmission of radiation in excess of a safe amount and means for supplying compressed gas to said outlet port to displace the mercury, forcing it into said sump passages and reservoir, and means for allowing the mercury to return to said outlet port to close off said beam.

3. An apparatus as in claim 2 wherein the means for supplying compressed gas includes a branched passage connecting a source of compressed gas to a point near the apex of the outlet port and to a point near the base of said outlet port at the upper end of the sloped window so that compressed gas will be supplied above the level of the mercury at any angle of tilt of the unit.

4. In a beam therapy unit which may be tilted about a horizontal axis including radioactive material providing a source of high energy gamma radiation within a container which absorbs radiation in excess of a safe quantity, apparatus for controlling the beam comprising a conical shaped outlet port, a sloped window sealing said outlet port to prevent mercury from escaping through the open end thereof while being capable of allowing the transmission of quantities of radiation of therapeutic value, a reservoir at a higher level than and laterally displaced in the direction of the higher end of the sloped window from said outlet port, having a base at an equal or greater slope than that of said window and having an equal or lesser slope than the base angle of said conical shaped outlet port, a sump capable of providing a mercury seal at all angles of tilt of the beam therapy unit, passages diverging on either side of the outlet port linking the base of the sump with the base of the reservoir, sufficient mercury with-

in said outlet port to prevent the transmission of radiation in excess of a safe amount and means for supplying compressed gas to said outlet port to displace the mercury forcing it into said sump passages and reservoir; said last mentioned means comprising a passage forking into an upper branch at a greater slope than said window connecting a source of compressed gas to a point adjacent to the apex of said outlet port and a lower branch at a lesser angle of slope than the base angle of the outlet port connecting the source of compressed gas to a point near the base of said outlet port and at the upper end of the sloped window so that compressed gas will be supplied above the level of the mercury at any 15 angle of tilt of the unit, and means for releasing the compressed gas from said outlet port to allow the mercury to return to said outlet port to close off said beam, and means for controlling the amount of mercury displaced and forced 20 into the reservoir.

5. An article as in claim 4 in which the means for controlling the amount of mercury displaced and forced into the reservoir comprises pressure responsive means operably connected to the 25 means for supplying compressed gas.

6. An article as in claim 4 in which means are provided to rotate the therapy unit through an angle of tilt defined by the position in which the window is horizontal and the position in 30 which the side of the outlet port opposite the base of the window is horizontal.

7. An article as in claim 4 wherein the means for supplying compressed gas comprises an electrically operated air compressor connected by 35 an air hose to said branched passages, and wherein the means for controlling the amount of mercury displaced comprises a pressure sensitive switch connected in series with the air compressor and responsive to changes in pressure 40 within the reservoir, and wherein the means for releasing the gas from the outlet port comprises a solenoid valve connected in parallel with the air compressor and the pressure sensitive switch, and wherein a switch is inserted in series with 45 both the air compressor and solenoid circuits.

8. In a beam therapy unit including a continuing source of radiation and a container having a low transmissibility to radiation enclosing said source and having an outlet port for the 50

10
15
20
25
30

emission of a beam, apparatus for controlling the beam comprising gravity operated means for supplying a liquid material of low transmissibility to radiation to close off said outlet port, means for removing said liquid material from the outlet port to open said outlet port comprising displacement of said liquid material from the outlet port to a higher level than said outlet port by compressed gas, means comprising said compressed gas for maintaining said liquid material exteriorly of said outlet port, means for releasing the compressed gas from the outlet port to allow the liquid material to pass into the outlet port to close off the beam and means having a high transmissibility to radiation to prevent said liquid material from escaping through the open end of said outlet port.

9. In a beam therapy unit including a continuing source or radiation within a container capable of absorbing radiation in excess of a safe quantity, apparatus for releasing and controlling a beam comprising an outlet port, a reservoir at a higher level than said outlet port sufficient high density liquid material within said outlet port to absorb radiation in excess of a safe amount, connecting means for transferring the liquid material between the base of said outlet port and the base of said reservoir, a window sealing said outlet port to prevent the liquid material from escaping through the open end of said outlet port while being capable of allowing the transmission of quantities of radiation of therapeutic value, means for forcing compressed gas into said outlet port to drive the liquid material from the outlet port into the reservoir releasing a beam of radiation and means for allowing the liquid material to return to said outlet port to close off said beams.
